UNITED STATES PATENT OFFICE.

CHARLES D. McCARTHY, OF ST. PAUL, MINNESOTA.

TIP-FORMING DEVICE FOR BILLIARD-CUES AND THE LIKE.

1,279,734.

Specification of Letters Patent. Patented Sept. 24, 1918.

Application filed October 19, 1916. Serial No. 126,473.

To all whom it may concern:

Be it known that I, CHARLES D. McCARTHY, a citizen of the United States, residing at St. Paul, in the county of Ramsey and State of Minnesota, have invented certain new and useful Improvements in Tip-Forming Devices for Billiard-Cues and the like; and I do hereby declare the following to be a full, clear, and exact description of the invention, 10 such as will enable others skilled in the art to which it appertains to make and use the same.

My invention relates to improvements in tip-forming devices for billiard cues and 15 the like; and, to this end, it consists of the novel devices and combinations of devices hereinafter described and defined in the claims.

In the accompanying drawings, which 20 illustrate the invention, like characters indicate like parts throughout the several views.

Referring to the drawings,

Figure 1 is a plan view of the invention, 25 with some parts shown in different positions by means of broken lines;

Fig. 2 is a side elevation of the same, with some parts broken away and with some parts shown in section;

Fig. 3 is a transverse vertical section taken 30 on the line 3—3 of Fig. 1;

Fig. 4 is a transverse vertical section taken on the line 4—4 of Fig. 1;

Fig. 5 is a bottom plan view of the cutter 35 head, with some of the associated parts sectioned on the line 5—6 of Fig. 2;

Fig. 6 is a plan view of the cam plate and centering jaws, with some of the associated parts sectioned on the line 5—6 of Fig. 2;

Fig. 7 is a view in side elevation of the 40 tip end of a billiard cue and also showing, in edge elevation, a knife in position for cutting a tenon on the billiard cue;

Fig. 8 is a plan view of a knife in position for trimming or smoothing the tip end 45 of a billiard cue at right angles to the axis thereof; and

Fig. 9 is a plan view of knives in position 50 for circumferentially trimming a billiard cue at the tip end thereof.

The numeral 1 indicates an annular cutter head, having a relatively large axial bore 2 and a pair of diametrically opposite and radially projecting finger pieces 3 with 55 knurled surfaces. A pair of diametrically

opposite and circumferentially extended slots 4 are formed in the cutter head 1, and formed in the top face of said cutter head, is a knife seat 5 and a gage block seat 6. These seats 5 and 6 are in the form of diametrically opposite and radially extended channels, which project from the bore 2 to the periphery of the cutter head 1 and at an angle to the slots 4. On the under face of the cutter head 1, is a depending peripheral flange 7, a way or channel 8 and a pair of spring pockets 9. The way 8 extends radially and completely across the cutter head 1 and into which the slots 4 extend. The spring pockets 9 are circumferentially 70 extended and are located, one on each side of the way 8.

Mounted on the bottom of the cutter head 1, is an annular cam plate 10, which closely fits within the flange 7 and is held thereby 75 against radial displacement. This cam plate 10 has a relatively large and irregular axial opening 11 and a pair of diametrically opposite cam slots 12, which extend into the way 8. Integrally formed on the periphery of the 80 cam plate 10, is a radially projecting finger piece 13 and on the upper face of said plate, is a pair of diametrically opposite lugs or abutments 14, which project into the spring pockets 9. A coiled spring 15 is compressed 85 between each abutment 14 and one end of the respective spring pocket 9. The cam plate 10 is secured to the cutter head 1 against axial displacement and in different circumferential adjustments by a pair of 90 shouldered set screws 16, which are loosely extended through the slots 4 and have screw-threaded engagement with the cam plate 10. Obviously, by loosening these set screws 16, the cam plate 10 may be oscillated on the cutter head 1 or, by tightening said set screws, the cam plate 10 may be frictionally clamped onto the cutter head 1 in different 95 circumferential adjustments.

Depending through the axial opening 11 100 in the cam plate 10, is a pair of cooperating centering jaws 17. These centering jaws 17 are in the form of channels, which extend parallel to the axis of the cutter head 1 and have diverging sides. Integrally formed 105 with the upper end of each jaw 17, and projecting laterally outward therefrom, is a slide 18 mounted in the way 8. These slides 18 support the centering jaws 17 from the cutter head 1, for rotary movement there- 110

with but with freedom for opening and closing movements around a billiard cue Y or other article. In each slide 18, is an oblique clearance slot 19, which extends parallel to the cam slots 12 and on the bottom of said slide is a depending cam pin 20. The set screws 16 extend through the clearance slots 19 to permit the required radial movements of the slides 18 and the cam pins 20 extend into the slots 12 to impart radial movement to the slides 18, under the oscillatory movement of the cam plate 10.

The numerals 21, 22 and 23 indicate knives of different shapes, but all having bodies of the same form, so as to snugly fit in the channel seat 5. A set screw 24, having screw-threaded engagement with the cutter head 1, is provided for detachably securing any one of the knives in the seat 5. Each knife 21 and 22 is provided with a transverse bore 25 to receive the set screw 24 and the knife 23 is provided with a slot 26, which permits the same to be adjusted radially into the bore 2 of the cutter head 1. The knife 21 is designed to cut a tenon Y¹ on the tip end of the billiard cue Y, and the knife 22 is designed to dress or smooth the tip of the cue Y at right angles to the axis thereof. The knife 23 is designed to circumferentially dress or trim the cue or tip applied thereto. As is well known, in applying a new tip to a billiard cue, the same usually varies slightly in diameter.

The depth of the cut made by the knives 21 and 22 may be regulated by a gage block 27 secured in the seat 6 by a set screw 28 and having its inner ends projecting into the bore 2 of the cutter head 1. By loosening the set screw 28, the depth of the cut made by either of the knives 21 or 22 may be increased, at will.

The operation of the invention may be briefly described as follows:—

The proper knife to do the work required is secured in the seat 5 of the cutter head 1 and the set screws 16 loosened. In applying the device to an article, such as a billiard cue, the same is held in one hand by one of the finger pieces 3 and with one finger on the finger piece 13 of the cam plate 10, the other hand being free to hold the article to which the device is to be applied. With the device thus held, a drawing pressure on the finger piece 13 will rotate the cam plate 10 against the tension of the springs 15 and open the centering jaws 17 to receive an article therebetween. When the finger piece 13 is released, the springs 15 rotate the cam plate 10 and move the centering jaws 17 onto the article, or cue Y. The cam slots 12 in the cam plate 10, acting on the cam pins 21 on the slides 18 of the centering jaws 17, cause said jaws to simultaneously move in opposite directions with equal radial movements onto the cue Y.

This equal movement of the centering jaws 17 causes the same to correctly and positively center the cue Y in the cutter head 1.

With the centering jaws 17 yieldingly held onto the cue Y, the set screws 24 are tightened to frictionally clamp the slides 18 between the cutter head 1 and cam plate 10 and thereby hold the centering jaws 17 into positive engagement with the cue Y. By providing the clamping jaws 17 with diverging sides, the same have contact with the cue Y at four distinct and circumferentially spaced points, thereby making the jaws adjustable to cues varying somewhat in diameter. With the cue Y properly held and centered by the jaws 17, the device is rotated by the finger pieces 3, on the cue Y to produce the cutting action. While rotating the device, sufficient pressure is applied thereto to hold the knife to its work. To remove the device from the cue Y, it is only necessary to loosen the screw 16 and permit the spring 5 to open the centering jaws 17. Under the rotary movement of the centering jaws 17, on the cue Y, a tenon will be cut on said cue at the true axis thereof.

In Fig. 9, a second knife 23 is diagrammatically illustrated and mounted in the seat 6. By using two of these knives 23 with their cutting edges acting on diametrically opposite points of the work, equal pressure is applied to said work, thereby holding the same against vibration, in order that the knives may do their work properly.

From the above description of the centering jaws 17, it is evident that their action, in centering the cutter head on an object, is entirely automatic.

What I claim is:—

1. In a device of the kind described, the combination with a revoluble cutter head having an axial opening, of a pair of slides mounted in the cutter head and having depending coöperating rigid centering jaws extending through the axial opening therein, cam actuated means under yielding strain to impart simultaneous and equal radial movements in opposite directions to the slides and their centering jaws.

2. In a device of the kind described, the combination with a revoluble cutter head having ways, of a cam plate rotatively mounted in the cutter head, a spring under strain to rotate the cam plate, coincident axial openings in the cutter head and cam plate, a knife carried by the cutter head and extending into the axial opening therein, slides mounted in said ways and having depending coöperating rigid centering jaws extending through the axial opening therein, and cam pin and slot connections between the cam plate and slides.

3. In a device of the kind described, the combination with a revoluble cutter head having ways, of a cam plate rotatively

mounted in the cutter head, a spring under strain to rotate the cam plate, coincident axial openings in the cutter head and cam plate, a knife carried by the cutter head and extending into the axial opening therein, slides mounted in said ways and having depending coöperating rigid centering jaws extending through the axial opening therein, cam pin and slot connections between the 10 cam plate and slides, and binding screws mounted in slots in the cutter head and slides and having screw threaded engagement with the cam plate.

4. In a device of the kind described, the 15 combination with a revolute cutter head having ways, and finger pieces, of a finger piece equipped cam plate rotatively mounted in the cutter head, a spring under strain to rotate the cam plate, coincident axial openings in the cutter head and cam plate, a knife carried by the cutter head and extending into the axial opening therein, slides mounted in said ways and having depending coöperating rigid centering jaws extending through the axial opening therein, and cam pin and slot connections between the 20 cam plate and slides.

25 5. In a device of the kind described, the combination with a revolute cutter head having in its top face a pair of radial seats and in its bottom face radial ways, of a cam plate rotatively mounted in the cutter head, a spring under strain to rotate the cam plate, coincident axial openings in the cutter head and cam plate, a knife and a gage block mounted in the radial seats in the top face 30

of the cutter head and extending into the axial opening therein, binding screws securing the knife and gage block in their respective seats, slides mounted in said ways and having depending coöperating rigid centering jaws extending through the axial openings therein, and cam pin and slot connections between the cam plate and slides. 40

6. In a device of the kind described, the 45 combination with a revolute cutter head having ways and a spring seat, of a cam plate rotatively mounted in the cutter head and having a lug projecting into said spring seat, a spring compressed between said 50 spring seat and lug and under strain to rotate the cam plate, coincident axial openings in the cutter head and cam plate, a knife carried by the cutter head and extending into the axial opening therein, slides 55 mounted in said ways and having depending coöperating rigid centering jaws extending through the axial opening therein, cam pin and slot connections between the cam plate and slides, and binding screws 60 mounted in slots formed in the cutter head and slides and having screw threaded engagement with the cam plate for holding said cam plate and slides in assembled relation in cutter head and for frictionally holding the same where set. 65

In testimony whereof I affix my signature in presence of two witnesses.
